UNITED STATES PATENT OFFICE.

DAVID S. KENNEDY, OF BROOKLYN, NEW YORK, ASSIGNOR TO MERGENTHALER LINOTYPE COMPANY, A CORPORATION OF NEW YORK.

LINOTYPE MACHINE.

No. 890,283.

Specification of Letters Patent. Patented June 9, 1908.

Application filed January 25, 1908. Serial No. 412,582.

To all whom it may concern:

Be it known that I, DAVID S. KENNEDY, of borough of Brooklyn, county of Kings, and State of New York, have invented a new and 5 useful Improvement in Linotype-Machines, of which the following is a specification.

My invention has reference to that class of line-casting or linotype machines wherein two or more sets or fonts of circulating matrices representing different type faces are stored in corresponding magazines, and the mechanism so constructed that matrices from two or more magazines may be composed in a common line when so desired, as 10 shown, for example, in United States Letters Patent No. 347,629. In this class of machines it is customary to use a primary distributing mechanism by which the matrices in the composed line, after use at the mold, 15 are separated according to fonts, the matrices, of the respective fonts being thereafter delivered to corresponding distributers by which the individual matrices are delivered to appropriate channels in the respective 20 magazines. In the practical operation of these machines it sometimes happens that individual matrices will be presented in improper positions, or delayed in their movement to the preliminary distributing mechanism. 25

It is the object of my invention to provide for the automatic stoppage of the distributing mechanism whenever this occurs; and to this end it consists in movably mounting 30 members of the font distributing mechanism and connecting them with a distributer driving clutch in such manner that the lodged or 35 improperly placed matrices, acting on said movable members, will cause the disengagement of the clutch and the stoppage of the 40 mechanism.

My improvement is susceptible of various modifications, which will suggest themselves to the skilled mechanic after consideration of 45 this specification and the accompanying drawings; but for the purpose of illustration I have shown my improvement embodied in distributing mechanism of the character represented in application of J. R. Rogers 50 for United States Patent, Serial No. 406,165, with the exception that the matrices in the present instance are permitted, after being separated, to pass downward by gravity to the individual distributers as in Patent 347,629.

55 I have limited the drawings to those parts

of the machine with which my improvements are immediately associated, and it is to be understood that all other parts may be of the ordinary or any suitable construction.

Referring to the drawings, Figure 1 is a rear elevation of the primary distributing mechanism and adjacent parts. Fig. 2 is a vertical cross-section on the line 2—2, Fig. 1. Fig. 3 is a perspective view showing in outline the principal parts of the mechanism and 65 clutch connections. Fig. 4 is a vertical longitudinal section on line 4—4, Fig. 2, illustrating the manner in which a lodged matrix effects the movement of the clutch controlling members. 70

Referring to the drawings: A represents the main frame work, which may be of any form and construction adapted to sustain the other parts.

B, B', B², etc. are the horizontal distributor bars along which the individual matrices are carried by the screws E, E', etc. and delivered into the upper ends of the vertically channeled throats C, C', etc. forming upward continuations of the magazines in which the 80 matrices are supported.

D, D', D², etc. are a series of tubes, one for each magazine, leading downward in divergent lines from the primary or font distributer, and delivering the matrices to the ordinary mechanism, by which they are directed to mechanisms for feeding them to the respective distributers, B, B', etc. These feeding mechanisms may be of the character shown in United States Patent 848,771, or 90 of any other suitable construction, these parts forming no part of the present invention.

Passing now to the primary or font distributer to which my invention relates: F 95 represents the so-called "distributer lift box" into which the composed line of matrices is delivered horizontally, in an endwise direction, as usual.

G is the vertically reciprocating finger by 100 which the matrices are lifted one after another from the end of the line in position to engage the teeth of distributer bar, H, overlying the tubes D, D', etc.

Each of the matrices, I, has its upper end 105 formed with a V notch with a series of distributing teeth therein to engage the corresponding teeth of the bar after the manner described in United States Patent 347,629. Each matrix, except those of one font, is also 110

provided in the lower end with notches, the matrices of different fonts having unlike notches, but all matrices of the same font being notched alike.

- 5   J, J', etc. are horizontal screws lying adjacent to the distributor in position to engage the edges of the elevated matrices in order to cause their movement along the bar H and over the upper ends of the tubes, D, D', etc.
- 10   The distributor bar H has its teeth cut away at points directly over the spaces between the tubes D, D', etc. in such manner that the matrices will cease to be supported by the bar while moving from one tube to the next—this that the matrices may be permitted to fall into the appropriate tubes. In order to sustain the matrices, however, so that they may, while advancing, repeatedly reengage the teeth of the bar until they arrive over the tubes into which they should fall, bridges or supports, K, K', etc. are located between the upper ends of the tubes and beneath the path of the matrices. These bridges have on their upper side horizontal teeth or ribs corresponding to the notches of the different fonts, so that as the matrices are carried forward one after another they will ride upon, and be sustained by, the ribs and thus caused to repeatedly reengage the distributor bar at their upper ends until each matrix arrives at the bridge the ribs of which correspond with its notches. At such point each matrix is permitted to fall astride of the ribs and to such level that its teeth cannot engage with the distributor bar, so that on reaching the mouth of the next tube, and riding off from the ribs, it is permitted to fall by gravity through the tube in its course to the distributor bar below. These parts are, or may be, identical with those shown in the Rogers United States application 406,165. In my improved construction, however, the bridges, K, K' etc. instead of being mounted rigidly in place as in the Rogers machine, are supported in, and form part of, a horizontally sliding block, L, seated to have a slight horizontal movement in the main-frame. This sliding block is held normally in operative position by a spring, 1, as shown in Fig. 4. When the parts are acting in a normal manner it remains at rest; when, however, a matrix, assuming an abnormal position, is carried by the following matrix forcibly against a bridge, as shown, for example, in Fig. 4, the bridge and its supporting frame will yield and move horizontally in the direction indicated by the arrows for the purpose of throwing the driving clutch out of action.
- 55   Any suitable clutch or intermediate connections may be employed, but I recommend the arrangement shown in Fig. 3, in which M represents a lever centrally pivoted to the main-frame with one end in position to be acted upon by the sliding block L, while the opposite end is connected to a lever, N, centrally pivoted to the main-frame and acting in turn on the horizontal bar O, which acts at one end on the plate, P, turning about a horizontal axis, p. This plate has at one end an arm which engages the depending arm of a rock shaft, Q, turning on a horizontal axis and carrying at its opposite end an arm, q, acted upon by a spring, q', and controlling the clutch, R, through which the distributing mechanism receives motion from a constantly driven pulley, S. The clutch and its controlling device may be of the form shown, or identical with those used in commercial linotypes of the present day. Whenever a matrix lodges against, or between, the bridges they yield and move the block, L, which, through the parts above described, releases the clutch tripping device, q, which immediately throws the clutch out of action. When the arm, q, is disengaged from the clutch the parts resume their original position and the distributor will continue its action.
- 60   The essence of my invention lies in movably mounting the bridges or detector plates H, which form a part of the distributing mechanism, and in connecting with the movable bridges means for controlling the driving mechanism, so that the action of the primary distributor will be arrested whenever the matrices assume improper positions therein.
- 65   While it is preferred to connect the yielding bridges with the clutch controlled thereby, the use of the bridges in the absence of such connection is advantageous in that improperly lodged matrices are permitted to yield or move to a limited extent, and in such manner as to relieve them and the adjacent parts from excessive strains. A slight movement of the bridge will frequently permit a lodged matrix to escape and continue its course.
- 70   It is to be noted that in my mechanism the bridges through which the clutch is controlled are members of the distributing mechanism proper; that is to say, they serve to determine the position of the passing matrices, and the points at which they are released. It is also to be noted that the bridges are stationary under ordinary conditions, and that they are moved by the matrices only when the latter are in an improper position.
- 75   Having described my invention, what I claim is:
1. In a matrix distributor, variant stationary distributing members, mounted to yield under the pressure of abnormally placed matrices, in combination with distributor driving mechanism controlled thereby.
2. In a distributor, the yielding matrix sustaining bridges in combination with a distributor driving clutch controlled by the movement of the bridges.
3. The ribbed matrix sustaining bridges,

their sliding support, and a spring to hold the same in normal operative position.

4. The distributor bar with interrupted teeth, the feed screws, and the variant matrix sustaining bridges, in combination with their movable support and the spring to hold the same in operative position.

In testimony whereof I hereunto set my hand this 22d day of January, 1908, in the presence of two attesting witnesses.

DAVID S. KENNEDY.
